[57] CLAIM

The ornamental design for a simulative alarm clock housing, substantially as shown and described.

DESCRIPTION

FIG. 1 is a front perspective view of a simulative alarm clock housing showing my new design;

FIG. 2 is a front elevational view thereof;

FIG. 3 is a rear elevational view thereof;

FIG. 4 is a right side elevational view thereof, the left side being a mirror image thereto;

FIG. 5 is a top plan view thereof; and

FIG. 6 is a front perspective view of another embodiment of my new design of FIGS. 1-5 wherein the "door" has been omitted, all other views being identical.
